William A. Geiger

By Henry Fuchs. Atty.

UNITED STATES PATENT OFFICE

WILLIAM A. GEIGER, OF CHICAGO, ILLINOIS, ASSIGNOR TO W. H. MINER, INC., OF CHICAGO, ILLINOIS, A CORPORATION OF DELAWARE

COUPLER AND YOKE CONNECTION

Application filed November 2, 1931. Serial No. 572,615.

This invention relates to improvements in coupler and yoke connections.

One object of the invention is to provide in a coupler and yoke connection simple and efficient means for attaching the shouldered butt of a coupler shank to the yoke including a locking block or plate having shouldered engagement with both the yoke and coupler butt, together with means for effectively locking the block or plate against accidental removal or loss.

Another object of the invention is to provide a connection of the character described in the preceding paragraph, wherein the means for locking the block against removal comprises interlocking devices on said block and the front follower of the railway draft rigging.

Other objects of the invention will more clearly appear from the description and claims hereinafter following.

In the drawing, forming a part of this specification, Figure 1 is a side elevational view of a yoke and the butt portion of a coupler shank, illustrating my improvements in connection therewith. Figure 2 is a horizontal, longitudinal sectional view, partly broken away, corresponding substantially to the line 2-2 of Figure 1. Figure 3 is a view similar to Figure 2, illustrating another embodiment of the invention. Figure 4 is a transverse, vertical sectional view, corresponding substantially to the line 4-4 of Figure 3, showing only the bottom arm of the yoke, the lower portion of the front follower of the draft rigging, and my improved locking block and retaining means in connection therewith. Figure 5 is a view similar to Figure 3, partly broken away at the forward end, illustrating still another embodiment of the invention. And Figure 6 is a transverse, vertical sectional view, corresponding substantially to the line 6-6 of Figure 5, showing only the bottom arm of the yoke, the bottom portion of the front follower of the railway draft rigging, and my improved locking and retaining means in connection therewith.

Referring first to the embodiment of the invention illustrated in Figures 1 and 2, my improved construction comprises broadly a

yoke A; a locking block B; and a front follower C having retaining means thereon for holding the locking block against lateral displacement.

The yoke A has top and bottom spaced, horizontally disposed arms 10 and 11 connected at their rear ends by a vertical end section 12 formed integral with said arms. The forward portion of the bottom arm 11 is downwardly offset with respect to said arm, as indicated at 13, said offset section being connected to the bottom arm 11 by means of an inclined portion 14. The section 13 of the bottom arm 11 extends forwardly beyond the front end of the top arm 10, as clearly shown in Figure 1, and the forward ends of said arms are connected by spaced side webs 15-15. The webs 15-15 are of the cross-section shown in Figure 2, the inner surfaces of the same being flared forwardly and outwardly so as to accommodate the shank of the coupler for lateral movement. The upper sections of the webs 15-15 are inclined forwardly and downwardly and are connected to the section 13 of the bottom arm of the yoke by means of short vertical sections 16-16. The rear edge portions of the vertical sections 16-16 provide transverse abutment faces 17-17 for the locking block B.

The locking block B is in the form of a platelike member having a transverse, upwardly extending flange 18 at the outer end thereof. The flange 18 abuts the shoulders provided by the faces 17-17 of the web members 15-15. At the inner end, the platelike section of the locking block B is narrowed down to provide a rearwardly extending tongue 19 for a purpose hereinafter described. The locking block B is adapted to have shouldered engagement with the butt of the coupler, which is indicated by 20. As clearly shown in Figure 1, the butt portion of the coupler 20 has top and bottom transverse shoulders 21-21 at the forward side thereof, the bottom shoulder being engaged with the flange 18 of the locking block B. The upper arm 10 of the yoke is provided with a transverse interior shoulder 22 in alignment with the inner face of the flange 18 of the block 100

B, said shoulder 22 engaging the top shoulder 21 of the butt of the coupler 20.

The front follower C, which cooperates with the shock absorbing mechanism of the 5 railway draft rigging, is disposed within the yoke A and has a pair of forwardly projecting spaced fingers or arms 23—23 at the bottom thereof. The arms 23—23 slidably receive the tongue 19 of the locking block B 10 therebetween. As shown in Figure 1, the offset section of the arm 11 is of such a length as to permit the necessary rearward movement of the follower with respect to the yoke, the inclined section 14 of said bottom arm being 15 provided with spaced ribs 24—24, which present transverse abutment shoulders 25—25 at the forward ends thereof, which clear the follower C when in its innermost position. As will be evident, the locking block is held 20 against lateral displacement with respect to the yoke by means of the follower C, the follower C being held against lateral movement to any appreciable extent by being confined between the draft sills of the railway draft 25 rigging, said draft sills being indicated by 26—26 in Figure 2. As shown in dotted lines in said figure, the draft sills are provided with the usual front stop lugs 27—27 with which the follower C cooperates.

30 In assembling the coupler with the yoke, the butt of the coupler is entered between the arms of the yoke through the forward end thereof and the transverse upper shoulder thereof brought in alignment with the shoulder 35 22 of the top arm of the yoke. The coupler is then lifted so that the retaining block may be inserted between the bottom arm of the yoke and the coupler butt. The block is then inserted laterally of the yoke and the 40 flange 18 thereof engaged with the shoulders 17—17 of the webs 15—15 of the yoke and also with the lower shoulder 21 of the coupler butt. The follower C is then placed within the yoke rearwardly of the tongue 19 of the locking 45 block B, the fingers 23—23 of the follower C in this position clearing said tongue. The follower is then disposed so that the fingers 23—23 will engage on opposite sides of the tongue 19 of the locking block B. The follower C is then moved forwardly to the position 50 shown in Figures 1 and 2, where the fingers thereof engage the tongue 19 at opposite sides. When the coupler, together with the yoke and the other parts of the mechanism, is placed between the draft sills, the follower C will be held against any substantial lateral movement, thereby preventing lateral disengagement of the block B from the yoke A.

55 Referring next to the embodiment of the invention illustrated in Figures 3 and 4, my improved construction comprises a yoke D; a locking block E; and a front follower F. The yoke is of substantially the same design as the yoke A hereinbefore described and has 60 spaced side webs 115—115 connecting the top

and bottom arms at the forward ends thereof, which webs present transverse abutment faces 117—117 at their rear sides adapted to be engaged by the locking block E to hold the latter against forward movement with respect to the yoke. The locking block E has an upstanding transverse flange 118 at the forward end, similar to the flange 18 referred to in connection with Figures 1 and 2. The platelike portion of the locking block E is tapered rearwardly, as shown in Figure 3, and has a tongue member 119 rearwardly extending therefrom. The front follower, which is indicated by F, has a pair of depending, laterally spaced lugs 123—123, which embrace the 70 tongue 119 of the block E at opposite ends. The lugs 123—123 are of such a length as to extend downwardly beyond the locking block E and also embrace opposite sides of the bottom arm 111 of the yoke D. 75

80 It will be evident that when the parts shown in Figures 3 and 4 are assembled the follower will hold the locking block E against lateral displacement by means of the embracing lugs 123—123. As these lugs also embrace 85 opposite sides of the bottom arm of the yoke, the follower will be held against lateral displacement with respect to the yoke. Thus means in addition to the sills is provided for preventing any appreciable lateral displacement of the follower F.

85 Referring next to the embodiment of the invention illustrated in Figures 5 and 6, the yoke is indicated by G, the locking block by H, and the front follower by J. In this case, the locking block H is provided with a pair of rearwardly extending spaced arms 150—150 providing a guide slot 151 therebetween. The follower J is provided with a 90 central depending lug 152, which slidably engages within the slot 151, thereby holding the block H against lateral displacement with respect to the follower J. Inasmuch as the follower J is held against any appreciable lateral displacement by the draft sills, the locking block is held against lateral displacement with respect to the yoke by means 95 of the follower J. As in the forms of the invention shown in Figures 1 and 2, and 3 and 4, the locking block H of Figures 5 and 6 is provided with a transverse flange at the 100 forward end thereof, which engages the lower shoulder of the coupler butt. The forward end of the locking block H engages the shoulders provided by the side webs at the 105 forward end of the yoke in a manner similar to the blocks B and E hereinbefore described, thereby holding the locking block against 110 outward movement with respect to the yoke. 115

120 I have herein shown and described what I 125 now consider the preferred manner of carrying out my invention, but the same is merely illustrative and I contemplate all changes and modifications that come within the scope 130 of the claims appended hereto.

I claim:

1. In a coupler and yoke connection including a coupler having a shank provided with a shouldered butt, the combination with a yoke having top and bottom spaced arms connected at their inner ends by a vertical end section, and connected at their outer ends by spaced vertical side walls, the bottom arm of the yoke having a transverse abutment shoulder; of a locking block seated on said bottom arm and having its front end abutting said shoulder of the arm, said block having a transverse shoulder adapted to engage the lower shoulder of the coupler butt, said top arm having an interior shoulder engaging the top shoulder of the coupler butt; and a front follower within the yoke, said front follower and locking block having interengaging means thereon holding said block against lateral displacement with respect to said follower.

2. In a coupler and yoke connection including a coupler having a shank provided with a shouldered butt, the combination with a yoke having top and bottom arms connected at their rear ends by a vertical end member and having spaced connecting side walls at their front ends adapted to receive the coupler shank therebetween, said bottom arm having a transverse abutment shoulder; of means on the yoke abutting the shoulder of the coupler butt for connecting the coupler to the yoke, said means including a locking block seated on said bottom arm, said locking block abutting said transverse shoulder of the bottom arm of the yoke and being held thereby against forward movement with respect to the yoke; and a front follower within the yoke, said front follower and block having shouldered engagement on faces extending lengthwise of the yoke to hold said block against lateral movement with respect to the follower.

3. In a coupler and yoke connection including a coupler having a shank provided with a shouldered butt, the combination with a yoke having top and bottom arms connected at their rear ends by a vertical end member and having spaced connecting side walls at their front ends adapted to receive the coupler shank therebetween, said bottom arm having a transverse abutment shoulder; of a locking block seated on said bottom arm, said locking block abutting said transverse shoulder of the bottom arm of the yoke and being held thereby against forward movement with respect to the yoke, said block supporting the coupler butt and having shouldered engagement therewith, said butt being held against vertical displacement between the block and the top arm of the yoke; and a front follower within the yoke, said front follower and locking block having interengaging tongue and groove formations extending lengthwise of the yoke to hold said block against lateral

displacement with respect to the front follower.

4. In a coupler and yoke connection including a coupler having a shank provided with a shouldered butt, the combination with a yoke having top and bottom arms connected at their rear ends by a vertical end member and having spaced connecting side walls at their front ends adapted to receive the coupler shank therebetween, said bottom arm having a transverse abutment shoulder; of a locking block seated on said bottom arm, said locking block abutting said transverse shoulder of the bottom arm of the yoke and being held thereby against forward movement with respect to the yoke, said block having shouldered engagement with the bottom shoulder of the coupler butt, said block having an upper supporting surface for the coupler butt, said surface being spaced from said top arm of the yoke a distance corresponding substantially to the height of said butt of the coupler shank; and a front follower within the yoke, said front follower having a pair of laterally spaced fingers embracing the locking block on opposite sides to hold said block against lateral displacement with respect to said front follower.

5. In a coupler and yoke connection including a coupler having a shank provided with a shouldered butt, the combination with a yoke having top and bottom arms connected at their rear ends by a vertical end member and having spaced connecting side walls at their front ends adapted to receive the coupler shank therebetween, said bottom arm having a transverse abutment shoulder; of a locking block seated on said bottom arm, said locking block abutting said transverse shoulder of the bottom arm of the yoke and being held thereby against forward movement with respect to the yoke, said block having an upstanding front rib spaced from the top arm of the yoke a distance less than the overall height of the coupler butt, said rib engaging the front face of the bottom of said butt; and a front follower within the yoke, said locking block having a rearwardly extending tongue and said front follower having a pair of forwardly extending, laterally spaced fingers embracing said tongue and slidably receiving the same therebetween to hold said block against lateral displacement with respect to said front follower.

6. In a coupler and yoke connection including a coupler having a shank provided with a shouldered butt, the combination with a yoke having top and bottom arms, connected at their rear ends by a vertical end member and having spaced connecting side walls at their front ends adapted to receive the coupler shank therebetween, said bottom arm having a transverse abutment shoulder; of a locking block seated on said bottom arm, said locking block abutting said transverse shoul-

der of the bottom arm of the yoke and being held thereby against forward movement with respect to the yoke, said block having an upstanding projection spaced from the top arm 5 of the yoke a distance less than the overall height of the coupler butt and engaging the lower shoulder of said butt; and a front follower within the yoke, said locking block having a pair of rearwardly extending spaced 10 fingers and said follower having a depending lug slidably engaged between said fingers to hold said block against lateral displacement with respect to the front follower.

7. In a coupler and yoke connection including a coupler having a shank provided with a shouldered butt, the combination with a yoke having top and bottom arms connected at their rear ends by a vertical end member and having spaced connecting side walls at 15 their front ends adapted to receive the coupler shank therebetween, said bottom arm having a transverse abutment shoulder; of means on said yoke having shouldered engagement with the coupler butt for connecting 20 the coupler to the yoke, said means including a locking block seated on said bottom arm, said locking block abutting said transverse shoulder of the bottom arm of the yoke and being held thereby against forward 25 movement with respect to the yoke; and a front follower within the yoke, said front follower having a pair of depending spaced lugs embracing said locking block on opposite 30 sides to hold the block against lateral displacement with respect to said follower.

8. In a coupler and yoke connection including a coupler having a shank provided with a shouldered butt, the combination with a yoke having top and bottom arms connected 35 at their rear ends by a vertical end member and having spaced connecting side walls at their front ends adapted to receive the coupler shank therebetween, said bottom arm having a transverse abutment shoulder; of means on 40 said yoke having shouldered engagement with the coupler butt for connecting the coupler to the yoke, said means including a locking block seated on said bottom arm, said locking block abutting said transverse shoulder of the bottom arm of the yoke and being held thereby against forward movement with 45 respect to the yoke; and a front follower within the yoke, said front follower having a pair of depending spaced fingers embracing the locking block on opposite sides and also 50 slidably receiving the lower arm of the yoke therebetween, thereby holding the locking block against lateral displacement with respect to both the follower and the yoke.

60 In witness that I claim the foregoing I have hereunto subscribed my name this 29th day of October, 1931.

WILLIAM A. GEIGER.
